Primary Examiner — Catherine A Tuttle(74) *Attorney, Agent, or Firm* — Fross, Zelnick, Lehrman & Zissu, PC; Charles T. J. Weigell, Esq.(57) **CLAIM**

The ornamental design for a bottle, as shown and described.

DESCRIPTION

FIG. 1 is front perspective view of a bottle showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is an exploded perspective view thereof.

The broken lines depict the portions of the bottle that form no part of the claimed design.

1 Claim, 7 Drawing Sheets(56)
